CLAIM

The ornamental design for stethoscope, as shown and described.

DESCRIPTION

FIG. 1 is a left front perspective view of our stethoscope design;

FIG. 2 is a rear perspective view thereof;

FIG. 3 is a front perspective view thereof;

FIG. 4 is a right side perspective view of our design, the left side being a mirror image thereof;

FIG. 5 is a bottom plan view thereof;

FIG. 6 is a right rear perspective view of an alternate embodiment thereof; and,

FIG. 7 is a left front perspective view thereof.

Tubing shown in certain views is omitted in other views for ease of illustration. The tubing is of indeterminate length.
